UNITED STATES PATENT OFFICE.

WILLARD H. KEMPTON, OF WILKINSBURG, PENNSYLVANIA, ASSIGNOR TO WESTINGHOUSE ELECTRIC & MANUFACTURING COMPANY, A CORPORATION OF PENNSYLVANIA.

PROCESS OF AND APPARATUS FOR MOLDING.

1,357,238.

Specification of Letters Patent.

Patented Nov. 2, 1920.

Application filed October 17, 1918. Serial No. 258,623.

To all whom it may concern:

Be it known that I, WILLARD H. KEMPTON, a citizen of the United States, and a resident of Wilkinsburg, in the county of Allegheny and State of Pennsylvania, have invented a new and useful Improvement in Processes of and Apparatus for Molding, of which the following is a specification.

My invention relates to molds and more particularly to molds for use in molding bodies of insulating material such as articles comprising superimposed layers of fibrous sheet material, wood flour, asbestos or other fillers impregnated with a suitable binder such as a phenolic condensation product which may be hardened under the application of heat and pressure.

Oftentimes in the electrical arts it is desirable to form a tubular body of insulating material provided with a collar or shoulder also of insulating material. An example of such a product is the fairlead bushing for the antenna wires of aeroplane wireless installations. The primary object of my present invention resides in the provision of a mold capable of simultaneously molding the tubular body and its associated collar or shoulder, even though the two parts be formed of different materials.

In this connection, a further object of my invention resides in providing a mold which is simple in construction, has but a few parts and may be easily and conveniently operated.

With these and other objects in view, my invention will be more fully described, illustrated in the drawings, in the several views of which corresponding numerals indicate like parts, and then particularly pointed out in the appended claims.

Figure 1 is a top plan view of my improved mold, a portion of the cover plate being broken away; Fig. 2 is a longitudinal vertical sectional view taken on the line II—II of Fig. 1; Fig. 3 is an end elevation of the mold; Fig. 4 is an end elevation of certain spacer bars employed during the molding operation; Fig. 5 is a perspective view of one of the forming members employed in my mold, and Fig. 6 is a transverse sectional view taken substantially along the line VI—VI of Fig. 2, showing the assembly of certain of the mold parts at one stage of the molding operation.

In order to insure a clear understanding of the mold construction and the manner of employing it, I will first describe the article to be molded. This article is a fairlead bushing comprising a tubular body 1, formed by winding a plurality of superimposed layers of impregnated fibrous sheet material, such as paper, about the mandrel 2, and a collar or shoulder 3 formed about the tubular body adjacent one end and tapering toward its ends as clearly shown in Fig. 2. This collar may be formed of any suitable molding composition such as wood flour and a proper binder. Preferably, I employ a phenolic condensation product both as the impregnated agent of the sheet material and as the binder for the wood flour.

My improved mold body 4 may be made of any suitable material, such as steel and in any desired size and is formed with longitudinally aligned communicating mold chambers 5, 6 and 7 opening through the top and bottom of the body with their walls vertically disposed. The mold chamber 5 is substantially rectangular in shape and of considerable length in comparison with the mold chamber 7, which is also rectangular in shape. The intermediate mold chamber 6 is somewhat less in width centrally, than the mold chambers 5 and 7 and tapers from its center to its ends where it communicates with these chambers. The outer end walls of the chambers 5 and 7 are provided centrally with vertically formed channels 8 adapted to receive the ends of the cylindrical mandrel 2 and support it longitudinally of the mold chambers 5, 6 and 7 as clearly indicated in dotted lines in Fig. 1 and in full lines in Fig. 2.

The body 4 of my mold is formed along its upper and lower longitudinal edges with laterally projecting flanges 9 as best shown in Fig. 3. The mold body rests upon a bottom plate 10 which has upwardly directed flanges 11, the inner faces of which are undercut to loosely receive the flanges of the mold body and to provide wedge faces 12 in spaced relation of the upper surfaces of the mold body flanges. A top or cover plate 13 corresponding to the bottom plate is provided and has flanges 14, the inner faces of which are undercut in the same manner to provide wedge faces 15. Wedges 16 are provided which may be driven into the space be-

tween the flanges of the top and bottom plates and those of the mold body to firmly hold the plates in position.

Top and bottom splits 17 and 18 and side splits 19 are adapted to surround one end portion of the tubular body 1 and will be disposed within the chamber 5 and the outer faces of the side splits are downwardly and outwardly inclined for engagement with the 10 inclined faces of pressure-applying wedges 20 which may be driven or forced into the mold chamber 5 between its side walls and the side splits to force the latter into engagement with the tubular body 1. Corresponding top, bottom and side splits and wedges, bearing similar reference numerals, are provided for molding the other end portion of the tubular body disposed within the chamber 7. The inner faces of all of these 20 splits are, of course, grooved or channeled in such a manner that when they are brought to assembled position they provide a cylindrical chamber of the proper diameter.

Upper and lower forming members 21 and 25 22 are provided for use in the molding chamber 6 being externally shaped to completely fill this chamber and internally recessed to mold the collar 3. The cover plate 13 is formed with an opening 14' corresponding 30 in shape and size to the shape of the mold chamber 6 and a closure plate 23 is provided for this opening having depending centering studs 24 engageable in openings 25 provided in the upper surface of the upper 35 forming member.

While the above described structure constitutes, properly speaking, the entire mold, I employ, during the molding operation, a pair of spacer bars 26 of a length somewhat 40 greater than the length of the mold body and preferably formed at one end with an opening.

The method of molding bushings with my improved mold will be readily understood 45 from a consideration of the drawings, and only a brief description is believed to be necessary. To prepare the mold for reception of the article to be molded, the mold body is positioned upon the bottom plate, 50 the bottom splits and bottom forming member are placed therein and the spacer bars are inserted between the bottom plate and the mold body to support the latter in a slightly raised position with respect to the bottom 55 splits which rest upon the bottom plate.

The tubular body 1 upon its mandrel 2 is then positioned in the mold, the side splits for each molding chamber are disposed against the sides of the tubular body with 60 their lower ends resting upon the spacer strips and the wedges are applied and are forced in by placing the thus far assembled mold in a heated press. This much of the molding operation forces the side splits into 65 their final position with respect to the tubu-

lar body and into engagement with the bottom splits. At the same time the material of the tubular body is free to expand somewhat above and below by reason of the space provided by permitting the bottom splits to 70 drop between the spacer bars and to the fact that the upper splits have not as yet been applied.

The mold is then removed from the press, the spacer bars are removed, permitting the 75 body of the mold to move as close to the bottom plate as the bottom splits engaging the tubular body will allow and the top splits are positioned above the tubular body and between the upper portions of the side 80 splits. The top or upper plate is then applied and the wedges are driven in to temporarily bind the top and bottom plates in place after which the mold is again positioned in the heated press to force the top 85 plate against the upper split and subsequently against the top of the mold and to force the mold, as a whole, against the bottom plate so that the top and bottom splits are brought to their final position relative to 90 the tubular body.

Inasmuch as during this last application of pressure, the side splits are at all times in close engagement with the top and bottom splits, there is no opportunity of escape or 95 pinching off of material and a close shutting off of the mold is insured. The wedges are now driven home and the mold is again removed from the press after which a suitable quantity of a molding composition, 100 such as wood flour impregnated with a phenolic condensation product, is passed through the opening of the cover plate into the molding chamber 6. The upper forming member is then positioned in the chamber 6 105 and the closure for the opening of the top plate is applied after which the now wholly assembled mold is positioned in a heated press and kept there until both the tubular body and its collar have been rendered hard 110 and solid.

After molding has been completed, the wedges may be driven out, the top and bottom plates removed and the various splits, 115 wedges and forming members may then be knocked from the mold body to release the finished product.

Although I have illustrated a mold adapted solely for molding a particular object, it will be appreciated that the novel principles, of mold construction disclosed, are such that with slight changes molds of the same character may be provided for molding bodies of various designs. It will, therefore, be understood that I do not wish any limitations imposed upon my invention, other than those set forth in the appended claims.

I claim as my invention:

1. A mold including a mold body formed with aligned communicating chambers, means 130

- for supporting a tube-carrying mandrel in the chambers, means disposable in one chamber to compress and mold the portion of tube located therein and means disposable in another chamber to compress and mold a body of moldable material about that portion of the tube located therein and also to compress and mold such portion of the tube. 40
- 5 2. A mold including a body formed with a chamber opening through its top and bottom, top and bottom plates for closing the chamber, a bottom forming member disposed in the chamber, side forming members adapted to receive an article between them, 45
- 10 wedges forcing the side members against the article and against the bottom forming member, a top forming member inserted between the wedges and coöperating with the bottom forming member to further compress the 50
- 15 article and means for clamping the top and bottom plates in place. 55
- 20 3. A mold including a body formed with a chamber opening through its top and bottom, a plurality of forming members adapted to surround an article and to compress and mold it when forced into the chamber, 60
- 25 top and bottom plates closing the chamber and means for securing the top and bottom plates in place. 65
- 20 4. A mold including a body formed with a chamber opening through its top and bottom, a plurality of forming members adapted to surround an article and to compress and mold it when forced into the chamber, 70
- 30 top and bottom plates closing the chamber and means for securing the top and bottom plates in place, said means including over-
- 35 lapping flanges upon the body and plates and wedges adapted to be driven between the flanges of the body and those of the plates. 40
- 40 5. A mold including a body formed with alined communicating chambers, means for supporting a tube-carrying mandrel in the chambers, means disposable in one chamber to compress and mold the portion of tube 45
- located therein, means disposable in another chamber to compress and mold a body of moldable material about that portion of the tube located therein, a cover for the mold having an opening through which the second chamber is exposed, means for securing the cover in place and a closure for the opening in the cover. 50
- 50 6. A mold including a body formed with a chamber opening through its top and bottom, top and bottom plates for closing the chamber, a bottom forming member resting upon the bottom plate, spacer bars insertible between the body and bottom plate, side forming members adapted to receive between them an article to be molded and to be positioned within the chamber at opposite sides of the bottom forming member, wedges adapted to be forced into the chamber to press the side forming members against the 60
- 55 article to be molded and against the bottom forming member, and a top forming member insertible between the upper portions of the side forming members. 65

In testimony whereof, I have hereunto 70
subscribed my name this 25th day of Sept.
1918.

WILLARD H. KEMPTON.
